(57) **CLAIM**

The ornamental design for an auxiliary tractor tank as shown and described.

DESCRIPTION

FIG. 1 is a top front side perspective view of an auxiliary tractor tank showing my new design;

FIG. 2 is a bottom rear side perspective view of the auxiliary tractor tank;

FIG. 3 is a front view of the auxiliary tractor tank;

FIG. 4 is a rear view of the auxiliary tractor tank;

FIG. 5 is a left side view of the auxiliary tractor tank;

FIG. 6 is a right side view of the auxiliary tractor tank;

FIG. 7 is a top view of the auxiliary tractor tank; and,

FIG. 8 is a bottom view of the auxiliary trailer tank.

The broken lines define borders inside which form no part of the claimed design.
